(57) **CLAIM**

We claim the ornamental design for a mower front frame, as shown and described.

DESCRIPTION

FIG. 1 is a front isometric view of the mower front frame, showing our new design;

FIG. 2 is a front-elevational view of the mower front frame; FIG. 3 is a left side-elevational view of the mower front frame;

FIG. 4 is a top view of the mower front frame;

FIG. 5 is a right side-elevational view of the mower front frame;

FIG. 6 is a rear-elevational view of the mower front frame; and,

FIG. 7 is a bottom view of the mower front frame.

The broken line showing of a mower is included for the purpose of illustrating environmental structure only and forms no part of the claimed design.
